CLAIM

The ornamental design for a solar wedge light, as shown and described.

DESCRIPTION

FIG. 1 is a top and front perspective view of a solar wedge light showing our new design;

FIG. 2 is a front elevational view thereof;

FIG. 3 is a back perspective view thereof;

FIG. 4 is a top plan view thereof;

FIG. 5 is a bottom plan view thereof; and,

FIG. 6 is a left side elevational view thereof, the right side elevational view being identical thereto.
